COMBINED VALVE ACTUATOR AND DISPENSING HEAD FOR A PRESSURIZED CONTAINER

Paul M. Kotuby, Naugatuck, Conn., assignor to The Risdon Manufacturing Company, Naugatuck, Conn., a corporation of Connecticut

Filed Jan. 5, 1966, Ser. No. 464

Term of patent 14 years

(Cl. D58—26)

FIG. 1

FIG. 2

FIG. 3

FIG. 4

FIG. 5

FIG. 1 is a front perspective view of a combined valve actuator and dispensing head for a pressurized container embodying my new design;

FIG. 2 is a front elevational view thereof;

FIG. 3 is a side elevational view thereof;

FIG. 4 is a top plan view thereof; and

FIG. 5 is a bottom plan view thereof.

I claim:

The ornamental design for a combined valve actuator and dispensing head for a pressurized container, substantially as shown.
